US00D515920S

(12) **United States Design Patent** (10) Patent No.: **US D515,920 S**
(45) Date of Patent: **** Feb. 28, 2006**

(54) **HAND HELD PRODUCT DISPENSER**

(75) Inventors: **David M. Groh**, Marshfield, MA (US);
John Howard Loudenslager, Phoenix,
AZ (US); **Jan R. Stillerman**, Phoenix,
AZ (US); **Marc Hunter**, Clayton, MO
(US)

(73) Assignee: **The Gillette Company**, Boston, MA
(US)

(**) Term: **14 Years**

(21) Appl. No.: **29/178,392**

(22) Filed: **Mar. 25, 2003**

(51) LOC (8) Cl. **09-07**

(52) U.S. Cl. **D9/448**

(58) Field of Classification Search D9/300,
D9/302, 350, 435, 436, 440, 442, 445, 452,
D9/447-450, 454, 520, 503-505, 529, 537,
D9/542, 545, 550, 682, 688, 689; 222/402,
222/321; 215/11.1, 235; D24/197

See application file for complete search history.

(57) **CLAIM**

The ornamental design for a hand held product dispenser, as shown and described.

DESCRIPTION

FIG. 1 is a front perspective view of a hand-held product dispenser;

FIG. 2 is a back side plan view thereof;

FIG. 3 is a front side plan view,

FIG. 4 is a left side plan view thereof;

FIG. 5 is a right side view thereof;

FIG. 6 is a top view thereof; and,

FIG. 7 is a bottom view thereof.

The broken line showing of the bottle in FIGS. 1 through 5 is for illustrative purposes only and forms no part of the claimed design.

1 Claim, 4 Drawing Sheets
